UNITED STATES PATENT OFFICE.

AUREN A. CUNNINGHAM, OF OMAHA, NEBRASKA, ASSIGNOR OF ONE-HALF TO
GARRETT P. WÜG, OF OMAHA, NEBRASKA.

MOP-BUCKET.

1,392,483.

Specification of Letters Patent.

Patented Oct. 4, 1921.

Application filed February 5, 1921. Serial No. 442,700.

To all whom it may concern:

Be it known that I, AUREN A. CUNNINGHAM, a citizen of the United States, residing at Omaha, in the county of Douglas and State of Nebraska, have invented certain new and useful Improvements in Mop-Buckets, of which the following is a specification.

The present invention relates to improvements in mop buckets, and has for an object to provide an improved bucket of this character in which are placed wringer rollers for squeezing the mop therebetween, the rollers being placed at one side of the bucket so as to allow a free space at the other side thereof for the introduction of the mop and its removal if desired without passage through the rollers.

Another object of the invention resides in providing an improved mop and wringer bucket of the character above indicated in which the construction is simple and cheap, and the operation of the device ready and efficient.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of an improved mop and wringer bucket constructed according to the present invention;

Fig. 2 is a vertical sectional view taken on the line 2—2 in Fig. 1 and looking in the direction of the arrow marked 10;

Fig. 3 is a fragmentary view along the same line 2—2 in Fig. 1 looking, however, in the direction of the arrow 11;

Fig. 4 is a plan view of a supporting arm;

Fig. 5 is a longitudinal central sectional view through one of the wringer rollers;

Fig. 6 is a side view of the plunger bracket.

Referring more particularly to the drawings, 12 indicates a bucket which is illustrated to be of the sheet metal type, but it is understood that the invention may be applied to buckets of other constructions and designs. The bucket 12 is provided with the usual bail or handle 13, and according to the invention I furnish the bucket near its base with a foot piece 14 extending from one side thereof in contact with the supporting

surface so that the foot may be placed thereupon to steady the bucket and prevent its being raised or tilted when the operator is in the act of drawing the mop upwardly through the wringer rollers as hereinafter described.

Within the bucket near one side thereof is a supporting bar 15 which extends across the bucket parallel with a diameter thereof so that the bar coincides substantially with a chord subtending an arc on the circle of which the bucket is made. The ends of the bar 15 are bent so as to lie against the walls of the bucket and are secured thereto by rivets or other suitable fastenings 16. The bar 15 is constructed with a lug 17 which is cut out from the body portion of the bar and bent at right angles. This lug 17 is perforated for a purpose to be later described.

The bar is also formed with a horizontally elongated slot 18 substantially centrally of the bar, and this slot 18 is formed substantially parallel and opposite to a similarly elongated slot 19 formed in an arm 20 which is riveted or otherwise secured to the wall of the bucket as indicated at 21 and extends into substantially the central portion of the bucket. The arm 20 lies parallel with the bar 15 and the two slots 18 and 19 are adapted to receive the unthreaded portions of the shanks of lag screws 22, which are threaded into the ends of a wooden or other roller 23.

The roller 23 is thus allowed to slide back and forth in a horizontal direction owing to the loose fit of the lag screws 22 in the slots 18 and 19. This permits the roller 23 to move back and forth with respect to a companion roller 24 also preferably made of wood, this roller being more particularly seen in Fig. 5 where it is illustrated to be also provided with lag screws 25 being pointed and threaded near their pointed ends. The screws are engaged with the ends of the roller 24 leaving the heads of the screws projecting a distance from the end walls of the roller in order to be received in perforations made in the bar 15 and a supporting bracket 26 which extends in alignment with the arm 20 and is riveted or otherwise secured to the bucket as indicated at 27. The roller 24 is thus free to turn about its trunnions which are formed by the lag screws 25, but it does not partake of any 110

horizontally sliding movement such as that to which the roller 23 is subjected.

The roller 23 is, however, constantly urged toward the roller 24 by means of plunger 5 brackets 28 more particularly illustrated in Fig. 6, which are provided with round perforations 29 to fit about the shanks of the lag screws 22. The brackets are provided with right-angular abutments 30 to which 10 are secured plunger rods or stems 31. One of the plunger rods 31 has a sliding fit through the perforation in the lug 17 on the bar 15, while the other plunger rod fits slidingly through a similar lug 32 cut out and 15 bent over from the arm 20. The plunger brackets themselves slide alongside the bar 15 and arm 20 respectively. Coil springs 33 are wound about the plunger rods 31 between the lugs and the abutments 30 and act 20 to normally urge the roller 23 toward its companion 24.

In the use of the device water or suds is placed in the bucket 12, and after each mopping operation the fabric portion of the mop 25 is introduced through the free space in the bucket at the side of the wringing device which is clearly shown in Fig. 1. The mop is worked into the suds or water several 30 times so as to cleanse it, and it is afterward passed through the space between the rollers 23 and 24 which will wring it out.

The springs 33 will develop sufficient pressure on the mop to squeeze it, but in case any foreign matter of a hard nature clings to the 35 fabric of the mop or any inequalities are found in its structure, the coil springs 33 will permit the roller 23 to yield, thus permitting the mop to pass through the rollers without the likelihood of injury thereto.

40 I do not wish to be restricted to the size, form, and proportions of the various parts, and obviously changes could be made in the construction herein described without departing from the spirit of the invention, it 45 being only necessary that such changes fall within the scope of the appended claims.

What is claimed is:

1. In combination with a bucket, a supporting bar mounted therein and provided

with a slot and a perforated lug bent at substantially right angles from the bar away from the adjacent side of the bucket, a pair of arms extending across substantially the central part of the bucket and lying approximately parallel with said bar whereby 55 to leave a large space at the the other side of said arms away from the bar clear, one of said arms being provided with a slot therein and a perforated lug bent toward said first mentioned lug, a pair of rollers provided 60 with trunnions extending therefrom, the trunnions of one roller being fitted in one of said arms and the bar, the trunnions of the other roller being slidably fitted in the slots in the other arm and bar, plunger 65 brackets connected to the trunnions mounted in said slots and having abutments, rods extending from the abutments and being slidable in said perforated lugs, and resilient means on said rods between the lugs and 70 abutments.

2. In combination with a bucket, a supporting bar mounted therein and provided with a slot and a perforated lug bent at substantially right angles from the bar, a pair of arms extending in substantial alignment across the central part of the bucket and lying approximately parallel with said bar and one of said arms provided with a slot therein, a pair of wooden rollers, lag 75 screws removably fitted in the ends of said rollers and having the heads spaced from said ends of the rollers, the lag screws of one roller being journaled in the bar and other arm, plunger brackets connected to the lag 80 screws mounted in said slots, said plunger brackets having abutments, rods extending from the abutments and being slidable in said perforated lugs, and coil springs wound about said rods between the lugs and abutments. 85

In testimony whereof, I have affixed my signature in presence of two witnesses.

AUREN A. CUNNINGHAM.
